APPARATUS FOR THE PRODUCTION OF
SPRING CLIPS

John Willy Siemss, Hamburg, Germany

Application February 10, 1939, Serial No. 255,685

4 Claims. (Cl. 140—82)

In order to secure the springs in spring and similar mattresses to the so-called edge wire surrounding them, wire clips are used according to the invention. These clips have in the middle an eye from which two arms extend outwards like wings one of which arms terminates in a hook and the other in an outwardly bent portion. The edge wire and the spring to be secured thereto are passed through the eye, whereas the two ends 10 of the clip bear against the edge wire. To produce sufficient tension when the clip bears against the edge wire and to ensure that the round spring is tightly clamped against the edge wire the above mentioned hook and bent out portion on 15 the ends of the clip arm must lie in different planes.

The production of such a clip is hereinafter described with reference to the accompanying drawing, in which:

Fig. 1 illustrates in elevation an apparatus partly broken away to show the bending of the clip in V-shape,

Fig. 2 shows a part of the apparatus partly in elevation and partly in section showing the last stage in the bending of the clip,

Fig. 3 is a side elevation showing a finished clip.

The invention is characterized in that the bend of the free ends of the clip 1 are first bent in the same plane, the arms being bent in V-shape as shown in Fig. 1. The free end 2 of one arm is bent in hook-shape and the end 3 of the other arm bent out of the straight line in an operation not illustrated as it is well known.

According to the invention this clip is now placed between two tools 4 and 5, the tool 4 being stationary and the tool 5 shiftable in bearings 6 and rotatable by means of a crank 7.

The tool 4 has in its centre a slot 8, in which the bend of the clip 1 is introduced. The tool 5, which has a projection 10 corresponding to a recess 9 in the tool 4, is shifted towards the tool 4 in the direction of the arrow so that the V-shaped clip 1 is brought into the spread position 1a shown in dotted lines in Fig. 1.

As the tool 5 is being shifted in the direction of the arrow 11, a disc 12 fixed on the same axle is shifted into the position 12a, with the result that the disc 12 which has an aperture 13 is moved past a pressure roller 14. This aperture 13 must be provided to enable the disc 12 to be shifted past the pressure roller 14 into the position 12a. Before shifting the disc 12 it must be turned until the aperture 13 is opposite the roller 14 whereupon by exerting pressure in the

direction of the arrow 11 the disc 12 is moved into the position 12a, the roller 14 passing through the aperture. This disc has a sloping face 12' so that, if the crank 7 is now turned and the tool 5 consequently rotated when the disc 12 is in the position 12a, the face of this disc directed towards the crank 7 will bear tightly against the pressure roller 14 so that the disc 12 is rigidly guided and the clip 1, in the position 1a, is held firmly between the tool 4 and the tool 5 in the position 5a while the following twisting operation is carried out.

If the crank 7 is turned for example through the angle of 45° an eye 1' is formed at the junction between the two arms, as shown in Fig. 2, which is a top plan view of Fig. 1. Only when the crank has been turned further, is the hook 1'' pulled downwards into the desired curvature, whereas the bending of the bent out end 1''' is effected by a tool 15 oscillatable about a pin 18. 15 By swinging this tool about the pin 18 in the direction 16 the bent out end 1''' is brought into the position shown in Fig. 3. It is important for the clip to be held absolutely firmly, this being attained by the pressure disc 12 and roller 14 above described.

After the lever 15 has been swung back and the crank 7 has been turned and slid back into its initial position the clip is finished. The stop 17 serves for bending the hook 1'' downwards into 30 the position shown in Fig. 3. In Fig. 2 the tool 5 has been omitted for the sake of clearness.

The apparatus described and illustrated is only given by way of example. It is evident that it can be mechanically driven instead of manually 35 and coupled with any known wire bending machine on which the wire is previously bent into the said V-shape, so that the production of the clip can be fully automatic. However, this production may also be carried out on two separate 40 machines, in which case the mechanically or manually operated apparatus shown in Fig. 1 is preferably supplied by hand with the V-shaped blanks.

I claim:

1. Apparatus for producing a clip for securing 45 springs to edge wires in spring mattresses and the like, comprising in combination a stationary tool adapted to firmly hold a V-shaped blank at the junction between the two arms of the blank, a second tool arranged coaxially with said stationary tool and having a recess adapted to receive the arms of the V-shaped blank, and means for axially shifting and rotating said second tool relatively to said stationary tool to bend an eye 50 at the junction of the two arms of the blank.

2. An apparatus as specified in claim 1, in which the means for axially shifting and rotating the second tool comprising a shaft carrying this second tool at one end, a disc keyed on said shaft at an intermediate point of the length thereof, said disc having an aperture in its periphery and a sloping face on the side remote from said second tool, a crank on the other end of said shaft adapted to axially shift and rotate said shaft with said disc to approach said second tool to said stationary tool, and a stationary roller in the path of movement of said disc, said roller adapted to pass through the aperture in said disc during the axial displacement of said shaft and to coop-

erate with the sloping face on said disc during the rotation of said shaft to press said second tool tightly against said stationary tool.

3. In an apparatus as specified in claim 1, abutments on the stationary tool, and abutments on the second tool in cooperative relation to the abutments on the stationary tool to bend over the free ends of the blank arms.

4. In an apparatus as specified in claim 1, an abutment in the stationary tool and a lever oscillatably mounted on said stationary tool in cooperative relationship to said abutment to bend over the end of one arm of the blank.

JOHN WILLY SIEMSS.
